(57) **CLAIM**

An ornamental design for a cigarette mini-pack with hinged lid, as shown and described.

DESCRIPTION

FIG. 1 is a perspective view of a cigarette mini-pack with hinged lid and beveled corners, showing our new design; FIG. 2 is a front elevational view of a cigarette package comprising a pair of the mini-packs of FIG. 1 before being overwrapped; FIG. 3 is a right side elevational view thereof, the left side elevational view being a mirror image duplicate; FIG. 4 is a rear elevational view thereof; FIG. 5 is a top plan view thereof, the bottom plan view being identical;

FIG. 6 is a perspective view of the cigarette mini-pack of FIG. 1 with the lid partially open;

FIG. 7 is a perspective view of a cigarette package comprising a pair of the mini-packs of FIG. 1 with overwrap and a tear strip; FIG. 8 is a perspective view of an alternative embodiment of a cigarette mini-pack with hinge lid and rounded corners, showing our new design; FIG. 9 is a front elevational view thereof; FIG. 10 is a right side elevational view thereof, the left side elevational view being a mirror image duplicate; FIG. 11 is a rear elevational view thereof; FIG. 12 is a top plan view thereof, the bottom plan view being identical; and,

FIG. 13 is a perspective view of a cigarette package comprising a pair of the mini-packs shown in FIG. 8 with overwrap and a tear strip.
